D. A. BOSWELL

PROTECTED PIN

Filed Aug. 1, 1924

INVENTOR.
DAVID A. BOSWELL.

BY
Franklin L. Seward

ATTORNEYS.

UNITED STATES PATENT OFFICE.

DAVID A. BOSWELL, OF INDIANAPOLIS, INDIANA.

PROTECTED PIN.

Application filed August 1, 1924. Serial No. 729,469.

To all whom it may concern:

Be it known that I, DAVID A. BOSWELL, a citizen of the United States, and a resident of Indianapolis, county of Marion, and 5 State of Indiana, have invented a certain new and useful Protected Pin; and I do hereby declare that the following is a full, clear, and exact description thereof, reference being had to the accompanying drawings, in which like numerals refer to like parts.

This invention relates to a safety pin having peculiar characteristics.

The chief object of the invention is to 15 construct a safety pin in such a manner that the normal tendency of the pin portion is to seat itself upon the catch portion and another object of the invention is to construct the catch or seat portion in such a manner 20 that the cooperating parts thereof may be associated together for positively locking the pin upon its seat and with the incidental feature in all instances of protecting or guarding the pin point.

25 An incidental feature of the invention, in addition to the accomplishment of the foregoing objects, is the arrangement of the coiled connection between the pin and the back, whereby the cloth is prevented from 30 becoming entangled with the several portions cooperating and forming said coil connection.

The full nature of the invention will be 35 understood from the accompanying drawings and the following description and claims:

In the drawings Fig. 1 is a perspective view of one form of the invention showing the parts in the normal position.

40 Fig. 2 is an end view thereof.

Fig. 3 is a perspective view of another and modified form of the invention.

Fig. 4 is an end view of the modification shown in Fig. 3.

45 Fig. 5 is a perspective view of the third modification of the invention.

Fig. 6 is an end view of the modification shown in Fig. 5.

50 In Figs. 1 and 2 of the drawings 10 indicates a loop of at least a single turn. One end of the loop is herein shown including an angular extension 11 which forms a pin terminating in the pointed end 12. The other end of the loop is also provided with 55 an angular extension 13, which herein is shown substantially parallel to the pin 11.

The end of said extension 13, however, is curved upwardly, rearwardly, and inwardly as at 14. It is also turned back upon itself to form another similarly curved portion 15, lying adjacent the first mentioned curved portion 14. These two portions 14 and 15 have a normal tendency, by reason of the resiliency in the wire forming the pin, to separate and leave the junction 16 of said curved portions in pin receiving or seat forming relation. The curved portion 15 is extended rearwardly as at 17 which adjacent the loop 10 is provided with an angular portion 18 that is suitably secured to the 60 pin portion 11 as indicated at 19.

The two parallel portions 13 and 17 constitute the back of the pin. They may be suitably secured together as by means of the ferrule 20. If desired, the aforementioned securing means may be omitted and other or equivalent means utilized. Soldering or welding may also be utilized. Also the two base portions 13 and 17 may be 70 twisted or coiled upon each other for securing the same in relatively rigid relation without departing from the broad feature 75 of the invention.

The curved portions, however, which form the pin receiving socket or seat are 80 separated and normally tend to separate. There is provided, therefore, a locking member in the form of a clip 21, the ends 22 of which are adapted to be slidably mounted upon the two curved portions 14 and 15. 90 Said locking member or clip constitutes a locking cam for as it is slid upon said curved portion and toward the point or junction thereof, said curved portions are caused to approach each other which not 95 only locks the pin in the seat, but prevents longitudinal movement therein.

As shown by the dotted lines in Fig. 1, said locking clip may be positioned such that it not only constitutes a locking member, but also a protective member. It covers the intervening space between the two curved portions 14 and 15 adjacent the seat 16 and thus covers the pin point when seated. As shown clearly by the dotted 105 lines and the arrow, the pin 11 is so associated with the back, that is, the coil connection is so wound, that the pin normally tends to seat itself in contra-distinction to the usual safety pin construction, wherein 110 the pin normally tends to position itself in open relation rather than in closed relation.

The advantages of the reverse construction disclosed herein are obvious although the chief one is that the pin will always be closed or seated when not positively actuated.

In Figs. 3 and 4 another and modified form of pin is shown and in this form of the invention the pin portion 111 is suitably connected to the coil connection 110, which in 10 this instance is of a different character from that shown in Fig. 1, but is similarly operative in that the pin normally tends to seat itself when released. The back portion 113 is also provided with the curved portion 114 15 at its free end, which is connected to a similarly curved portion 115 by the junction or seat 116. The back forming extension 117 lies parallel to the back portion 113 and is suitably secured thereto as by means of the 20 ferule 120 or equivalent means. The end 118 is suitably secured as at 119 so as to assist in the seating movement of the pin. The locking member 121 includes the curved member engaging portions 122 and the protective extension 123. The coiled connection 110 is so arranged that a lock is positioned at each 25 side of the plane including pin 111 and back 113.

This cooperation of the several parts is 30 substantially that previously described with reference to the form of the invention shown in Fig. 1. In Figs. 5 and 6 a further form of the invention is illustrated and in this form of the invention the pin 211 is 35 connected at one end to the coil portion 210, which in turn is connected to a base forming member 213 having the curved free end 214. Another member 217 is suitably connected in rigid relation by the ferule 220 or suitable 40 means previously pointed out and the portion 219 is adapted to secure the free end thereof, if necessary. The member 217 includes a curved portion 215 lying adjacent the curved portion 214 and the ends of said members are suitably connected together as 45 by means of the rivet 216.

A locking member 221 having the slidably supported portions 222 is adapted to be associated with the curved portions 214 and 50 215 in the same cooperative relation previously pointed out for similar parts in the other forms of the invention. In this instance, similar to Fig. 2, coiled connection 210 is arranged in balanced relation with 55 respect to pin 211 and seat 113.

From the foregoing, therefore, it will be readily apparent that various modifications of the invention will readily suggest themselves to those skilled in the art. These 60 modifications including those herein illustrated and described, are all considered to be within the broad purview of the invention, reference being had to the appended claims.

The invention claimed is:

65 1. A safety pin of the character described

including a back portion, a pin portion positioned adjacent thereto, a coiled connection connecting one end of the pin portion to the back portion so that the pin normally tends to position itself adjacent the back portion, 70 and a pin receiving seat construction having a pin receiving surface positioned in spaced relation to said back portion and connected thereto and engageable by said pin in the normal closing movement of said pin, said 75 surface preventing further movement of said pin toward said back portion.

2. A device of the character described in claim 1 characterized by the pin receiving seat including a U-shaped arrangement, the so intermediate portion of which is normally engageable by the pin and limits the movement of the pin toward the back portion.

3. A safety pin of the character described, including in combination a pin portion, a back portion resiliently connected thereto, a U-shaped pin receiving seat supported by said back and adapted to receive said pin at its intermediate portion, the arms of said U-shaped portion normally tending to separate, and means for causing said arms to approach each other and form a locked pin receiving seat.

4. A device of the character described in claim 3 characterized by the slidable mounting of the locking means upon said U-shaped seat, whereby said locking means is adapted to simultaneously serve as a pin point protector in cooperation with said seat.

5. In a safety pin construction of the character described, the combination of a pin, a back positioned adjacent thereto, a connection connecting one end of the pin to one end of the back and normally tending to force said pin to position itself adjacent said back, a U-shaped pin receiving seat supported by said back at its other end, including a pair of rearwardly and thence inwardly curved arms connected by an intermediate portion of pin receiving formation, 105 said arms normally tending to separate, and means for causing said arms to approach each other for pin retaining purposes.

6. A device of the character described in claim 5 characterized by the slidable mounting of the locking means upon the U-shaped seat, said locking means being adapted to cooperate with said seat adjacent the intermediate portion for protecting the pin point when seated upon said U-shaped seat.

7. A safety pin of the character described including a back portion, a pin portion positioned adjacent thereto, and a coiled connection connecting one end of the pin portion to the back portion, said connection comprising a plurality of coils positioned in spaced relation with respect to the plane including said pin portion and said back portion, whereby a balanced construction is obtained.

8. A device of the character described in claim 7 characterized by the coiling of said balanced connection to normally position the pin adjacent the back portion at all times.
9. A device of the character described in claim 7 characterized by the coiling of said balanced connection to normally position the pin adjacent the back portion and a pin

receiving seat construction having a pin receiving surface positioned in spaced relation to said back portion and connected thereto and engageable by the pin when unrestrained.

In witness whereof, I have hereunto affixed my signature.

DAVID A. BOSWELL.
